Assistant Examiner — Grace Doyle

(57) CLAIM

The ornamental design for a flora figure as shown and described.

DESCRIPTION

FIG. 1 is a front view of a flora figure showing my new design;

FIG. 2 is a rear view of the flora figure;

FIG. 3 is a left side view of the flora figure;

FIG. 4 is a right side view of the flora figure;

FIG. 5 is a top view of the flora figure;

FIG. 6 is a bottom view of the flora figure; and,

FIG. 7 is a top front side perspective view of the flora figure. The broken lines are illustrative of portions of the flora figure forming no part of the claimed design.
